UNITED STATES PATENT OFFICE.

HENRY D'OLIER, JR., OF BRIDGEPORT, CONNECTICUT.

COMBINATION HOOK AND LOOP.

Application filed October 12, 1925. Serial No. 61,879.

My invention relates to a combination hook and loop for supporting lighting fixtures and other similar devices from metal conduits and the like.

5 My invention will be better understood by reading the following description taken in connection with the accompanying drawings, in which

Fig. 1 is a side elevation of a hook;

10 Fig. 2 is a side elevation of a loop;

Fig. 3 is a view of the device of Fig. 1 or Fig. 2 rotated through an angle of 90 degrees;

15 Fig. 4 is a view similar to Fig. 3 with the upper portion arranged to receive a round conduit or support;

Fig. 5 is a view similar to Fig. 3 with the upper portion screw threaded; and

20 Fig. 6 is a view similar to Fig. 3 with the upper portion arranged to engage an outlet box or similar device.

It is often desirable in the supporting of lighting fixtures and other similar devices to provide loops or hooks depending upon the 25 circumstances of the particular case. It is also desirable in devices of this character to have as few parts as possible and to have the parts as simple as possible. It is also desirable from the dealer's point of view to 30 have as few parts as possible consistent with the assurance of having the necessary parts on hand to meet conditions as they arise in the trade. I have devised a device wherein only two parts are necessary to make either

35 a hook or a loop. As will be noted from Figs. 1 to 3, inclusive, the device consists of two pieces 1 and 2. As shown in Fig. 2, the part 1 has a hook portion 3 which extends to the right and then to the left forming the hook. It also has a portion 4 which extends 40 upwardly and an end which is bent over to surround the conduit 6 or other suitable support. The part 2 is similar to part 1 except it is reversed, that is to say, it has a hook portion 7 which extends to the left and then to the right to form the hook, and a portion

45 8 which extends upwardly and an end portion 9 which is bent to the right to surround the support. When the two parts are placed together, as shown in Fig. 3, the upper portions 4 and 8, and 5 and 9 substantially surround the support and act to firmly hold the device in place. The lower portion of such a device may take the form shown in Fig. 1 50 or as shown in Fig. 2. If two similar parts,

as for instance, the parts 1, are arranged so that their upper portions assume the position shown in Fig. 3, their lower portions will constitute a loop, as shown in Fig. 2, but if two oppositely arranged parts, as for instance 1 and 2, are placed together so that their upper portions assume the position shown in Fig. 3, then the lower portion will be as shown in Fig. 1, that is, to form a hook. In order that the parts may be securely fixed 60 together, an opening is provided and a screw bolt 10 passed therethrough and a nut 11 screwed onto the end of the bolt. Other means of fastening may be used.

The devices shown in Figs. 4 to 6, in so far as their lower portions are concerned, are identical with those shown in Figs. 1 to 3, but the upper portions are different. For instance, in Fig. 4 the upper portions 12 and 13 constitute a circle. In Fig. 5 they constitute a cup or cylinder 14 which is provided with screw threads 15 so that the same may be screwed onto the end of a pipe somewhat similar to screwing a cap onto the end of a gas pipe. The device shown in Fig. 6 is particularly adapted to attachment to a junction box wherein the sides 16 of the box are arranged with an opening between them and the parts 1 and 2 assembled in the position shown in Fig. 6 and the screw bolt 10 passed therethrough and fixed in position. The portions 17 and 18 extend horizontally and engage the upper surfaces of the parts 16 and thus support the device in place.

85 From the foregoing it will be evident that I have devised a device which has many advantages in practice in that by suitably selecting the similar and dissimilar parts a loop or a hook may be secured, and that by having the parts separable they may be easily 90 and quickly assembled and the advantages of both the hook and the loop may be secured without carrying a double stock of parts.

95 My invention has many other advantages which will be apparent to the practical man in the art.

I claim:

1. A support comprising two pieces of metal, each having a holding portion at one end and a supporting portion at the other 105 end, said holding portion being in the form of a hook if two unlike pieces are placed side by side throughout and being a loop if like pieces are placed side by side throughout.

2. A lighting fixture support comprising 110

two pieces of metal, each having a holding portion extending in one direction and a supporting portion extending transversely of the holding portion, said transverse portions 5 extending in relatively opposite directions to engage a supporting member, whereby when two unlike pieces are placed side by side throughout the holding portion takes the form of a hook, whereas when two like pieces 10 are placed side by side throughout the holding portion takes the form of a loop.

3. A lighting fixture support comprising two pieces lying side by side throughout, each 15 having a hook portion extending in one direction and a supporting portion extending transversely of the hook portion, said transverse portions extending in relatively opposite directions to engage a supporting member and said hook portions extending in relatively 20 opposite directions to form a loop.

4. A support comprising two flat pieces of metal, each having a hook portion lying in the plane of the respective piece and a supporting portion bent transversely outwardly, 25 upwardly and inwardly whereby a substantially closed supporting ring is formed when said pieces are placed side by side.

5. A support comprising two flat pieces of metal, each having a hook portion lying in 30 the plane of the respective piece and a supporting portion bent transversely outwardly, upwardly and inwardly whereby a substantially closed supporting ring is formed when

said pieces are placed side by side and means for holding said pieces together.

6. A lighting fixture support comprising two flat pieces of metal each having a hook portion extending edgewise of the metal, a supporting portion extending transversely of each of said pieces and in relatively opposite 40 directions whereby when said pieces are placed side by side a hook is formed of a thickness equal to that of both of said pieces and a supporting portion is formed by said transverse portions.

7. A support comprising two pieces of metal, one end of each piece having a hook portion lying in the plane of the respective piece, the other end having a grooved portion whereby when said pieces are fastened together they will comprise a threaded portion 45 at one end and a hook at the other.

8. A support comprising two pieces of metal, each having a hook portion at one end in the plane of the piece, the other end being 50 bent transversely, outwardly, upwardly and inwardly and means for fastening the two pieces together.

9. A support comprising two pieces of formed metal, each having a hook portion at 55 one end and a cylindrical threaded portion at the other whereby when said pieces are placed together longitudinally a device is provided having a threaded portion at one end and a hook portion at the other.

HENRY D'OLIER, JR.
